UNITED STATES PATENT OFFICE

131,250

DESIGN FOR A BOWL OR SIMILAR ARTICLE

Carl J. Uhrmann, Bellaire, Ohio, assignor to Imperial Glass Corporation, Bellaire, Ohio, a corporation of Ohio

Application May 24, 1941, Serial No. 161,125

Term of patent 14 years

To all whom it may concern:

Be it known that I, Carl J. Uhrmann, a citizen of the United States of America and resident of Bellaire, county of Belmont, and State of Ohio, have invented a new, original, and ornamental Design for a Bowl or Similar Article, of which the following is a specification, reference being had to the accompanying drawing, forming part thereof, in which:

Figure 1 is a top plan view of a bowl or similar article, showing my new design; and

Figure 2 is a side elevational view of the same. The characteristic feature of the design resides

in a bowl or similar article of the configuration shown having a series of ball elements disposed around the rim of the article in the manner shown, a plurality of said ball elements at diametrically opposite points being successively increased and decreased in diameter from the remaining ball elements of uniform diameter, as shown.

I claim:

The ornamental design for a bowl or similar article, substantially as shown and described.

CARL J. UHRMANN.
